PROCESS FOR IMPROVING HYDROCARBON OILS BOILING IN THE GASOLINE RANGE

George Cornelis Adriaan Schuit and Marius 't Hart, Amsterdam, Netherlands, assignors to Shell Development Company, Emeryville, Calif., a corporation of Delaware

No Drawing. Application June 2, 1952,
Serial No. 291,324

Claims priority, application Netherlands June 13, 1951

4 Claims. (Cl. 196—50)

This invention relates to a process for improving hydrocarbon oils of the gasoline boiling range by improving their knock stability, i. e., improving their anti-knock qualities. The invention relates to the improvement of the knock stability of gasolines and naphthas, particularly those which have been obtained directly from petroleum (i. e., straight-run gasoline and naphtha) and particularly those which have a relatively high content of naphthenic hydrocarbons. Although the process is particularly adapted for the treatment of straight-run naphthas of high naphthene content, it is also applicable for the treatment of other naphthenic hydrocarbon fractions of similar character.

The tendency for a gasoline to knock when used in an internal combustion engine is usually indicated by the octane number. In the following the knocking tendency will be expressed by the Motor Method octane number which is otherwise designated the ONF-2 number.

Gasolines obtained from petroleum by distillation, i. e., straight-run gasolines, and also certain cracked and synthetic gasolines, have poor anti-knock characteristics. It is well known that such gasolines can be materially upgraded by suitable thermal or catalytic treatment; such treatments to upgrade the gasoline are generally referred to as reforming treatments.

In any reforming treatment there is an appreciable loss of gasoline and in every case this loss increases sharply as the extent of upgrading is increased by the application of increasingly severe treating conditions. This loss is most important and limits the extent of upgrading which may be economically applied in any given case.

It is possible by thermal methods to upgrade the usual run of gasolines up to a certain point without excessive loss, and since thermal reforming is the least costly type of reforming process, such thermal reforming is preferred in all cases where the degree of upgrading is sufficient to meet the demands. Any attempt to upgrade the gasoline further by thermal reforming results in little improvement in octane number and prohibitively high losses.

During the past years the anti-knock requirements of gasoline have generally increased to the extent that the upgrading obtainable by thermal reforming is often not sufficient. It is, therefore, now becoming necessary to resort to a more costly catalytic reforming process. In catalytic reforming, as in thermal reforming, the yield decreases as the upgrading is increased. Catalytic reforming has the advantage over thermal reforming, however, in that at a given loss the octane number can be increased to a somewhat higher value. It is therefore possible to attain higher octane numbers in the important region of 80 F-2 and above. Various catalytic reforming processes have been proposed and, neglecting processing costs for the moment, these differ only in the yield octane number relationships obtainable in the critical high octane number region. An improvement of even one octane number at a given yield, or an improvement of

2

even 1% increased yield at a given octane number represents a very valuable and important improvement. This is particularly the case in the high-octane region above 80 F-2 since one octane number improvement in this region is worth several octane numbers in the lower regions.

The known and hitherto suggested catalytic reforming treatments generally involve treating the gasoline or naphtha in the vapor phase with a catalyst such as molybdenum oxide, chromium oxide, tungsten sulfide, nickel sulfide, or the like. These and other related catalysts are generally applied with inert carrier or support materials such as alumina, silica, pumice, and the like which provide an extended surface. When reforming gasolines with such catalysts a certain amount of dehydrogenation takes place and the gasoline is, among other things, made more aromatic in nature. It is recognized, however, that reforming is not a simple aromatization process and that the aromaticity (aniline point) of the product is not a proper criterion of the reforming efficiency. The loss of gasoline caused by the reforming treatment is due in part to a somewhat increased density of the reformed product, but is mainly due to conversion of a substantial part of the gasoline feed to gases, higher boiling products, and tar or coke. These losses are generally believed to be largely the result, directly or indirectly, of dealkylation, cracking, and condensation reactions.

While the mentioned catalytic reforming treatments are capable of upgrading all low octane gasolines they are much more efficient in the treatment of some gasolines than others. Those gasolines in which the proportion of carbon atoms found in polymethylene rings is large are generally most amenable to such treatment. However, those gasolines high in naphthenic hydrocarbon content have, on the other hand, in many cases, been most difficult to upgrade without large losses. This is due largely to the fact that the naphthenic hydrocarbons normally encountered in straight-run gasolines are generally approximately equally divided between those having hexamethylene rings (hydroaromatic hydrocarbons) and those having pentamethylene rings. The naphthenic hydrocarbons having pentamethylene rings are unable to withstand the required relatively drastic treating conditions without extensive cracking. Also, they are prone to be dehydrogenated to unsaturated products such as cyclopentadiene, which undergo secondary reactions with the formation of tarry substances which quickly coat the catalyst surface and render the catalyst ineffective. It is for this reason that it has frequently been suggested to selectively remove or destroy the major part of the naphthenic hydrocarbons having pentamethylene rings prior to any attempt to upgrade the gasoline by catalytic reforming.

The hydrocarbon oil may be a full range gasoline having an initial boiling point within the range of about 10° C. to about 38° C. and a final boiling point within the range of about 160° C. to about 225° C. or it may be a somewhat narrower range material sometimes referred to as naphtha having, for example, an initial boiling point between about 50° C. and about 130° C. and a final boiling point between about 155° C. and about 225° C.

Recently, it was discovered that through the use of a promoted platinum catalyst gasolines having a high concentration of naphthenic hydrocarbons can be more effectively upgraded, without recourse to prior treatment to remove or destroy naphthenic hydrocarbons having pentamethylene rings. In this process, known as the Platforming Process, a platinum catalyst is used in which the platinum is supported upon an alumina and promoted by a halogen, e. g., chlorine and fluorine. When using this special catalyst the naphthenic hydrocarbons having pentamethylene rings are largely converted to aromatic hydrocarbons by dehydroisomerization. If the

process is carried out under a sufficiently high partial pressure of hydrogen, dehydrogenation of the pentamethylene rings and consequent rapid deactivation of the catalyst can be substantially avoided. Substantial cracking of the naphthenes containing pentamethylene rings, nevertheless, takes place and the yields, although higher than obtainable by the previously known process using non-platinum catalysts, are not as high as theoretically possible and desired. The Platforming catalyst and process is described in U. S. Patent Numbers 2,479,109; 10 2,479,110; 2,478,916 and 2,573,149.¹

The suggested platinum catalysts are extremely sensitive to poisons, are very costly, and, up to the present time, there is no satisfactory method for repeatedly regenerating them to restore their initial activity. It would, therefore, be highly desirable to have available a process which combines the good points of the Platforming process while avoiding its shortcomings. It would be a great advantage if the quantity of platinum needed could be reduced or the use of platinum entirely avoided without having to sacrifice the advantages connected with the use of the Platforming catalyst. Experimentation has now shown that such a process is possible. Thus, excellent reforming of highly naphthenic gasolines may be obtained with the use of much less platinum or even while dispensing with platinum altogether.

In our copending application, Serial Number 292,439, filed June 9, 1952 (corresponding to Netherlands application Number 161,954), we have described a process using a platinum catalyst which is particularly designed and effective for the upgrading of gasoline and naphthas which contain only small concentrations of naphthenic hydrocarbons, e. g., less than 30%. In said process the upgrading of the gasoline is effected in two steps, in the first of which an acid cracking catalyst containing a dehydrogenation promoter is employed and in the second of which a dehydrogenation catalyst, which is devoid of any acidity or cracking activity, is employed. In said process the loss in yield due to cracking of naphthenic hydrocarbons having pentamethylene rings during the first stage of the treatment is not an important consideration since the concentration of such naphthenic hydrocarbons in the reaction mixture is quite low. When treating gasoline fractions which are concentrated in naphthenic hydrocarbons, i. e., have above 30% naphthenes, on the other hand, the loss in yield when treating according to the method of said copending application is relatively high.

In the process of the present invention gasolines having such high concentration of naphthenic hydrocarbons, including those having pentamethylene rings, are upgraded with low loss by a two stage process in which the catalyst and conditions in the first step are adjusted such that naphthenic hydrocarbons having pentamethylene rings are substantially unaffected while the naphthenic hydrocarbons having hexamethylene rings are dehydrogenated. In the second step of the process the conditions and catalyst are chosen to complete the upgrading of the gasoline through various other reactions, including conversion of the naphthenic hydrocarbons having pentamethylene rings.

In the process of this invention the gasoline is first partly reformed by treating it in the vapor phase and in the presence of hydrogen with a dehydrogenation catalyst which has little, if any, cracking activity (acidity) and is capable of selectively dehydrogenating the naphthenic components of the gasoline having hexamethylene rings. The essential prerequisite of such a catalyst is that it be substantially devoid of any appreciable acidity (cracking activity). The dehydrogenating promoter may be an oxide or a sulfide or one of the dehydrogenating metals, e. g., titanium, vanadium, chromium, manganese, nickel, molybdenum, cobalt, ruthenium, rhodium, pal-

ladium, tungsten, iridium, platinum, and thorium. These metals may be applied per se, but are more generally applied in combination with an inert support or carrier material. It is essential, however, that the support or carrier material is not acidic in character. Thus, such materials as pure alumina, pure silica, activated carbon, magnesia and the like may be used, but such materials as clays, silica-alumina composites, silica-magnesia composites, and various acid-treated carriers should not be used. One suitable catalyst consists of pure silica impregnated with 0.1 to 1% of platinum. A platinum catalyst is recommended in the first stage since it has very strong dehydrogenation properties and therefore allows a high rate of throughput to be applied. On the other hand, a non-platinum-containing catalyst can also be applied. An example of one such suitable catalyst is one which consists of a combination of the sulfides of tungsten and nickel. This catalyst sometimes exhibits an appreciable acidity as freshly prepared, but this is lost after a short period of use. The tungsten sulfide nickel sulfide may be applied with a carrier such as alumina, but not with a carrier activated with acid, particularly with hydrofluoric acid. Carriers of the latter type cause undesired cracking with loss of output under the treating conditions applied. When using a catalyst which does not contain platinum the catalyst may contain an alkali such as potassium. The presence of the alkali prevents the existence of any undesired acidity which may otherwise be present or be developed in the catalyst.

The reforming of the gasoline is completed by treating the partially converted product either with or without intermediate separation of hydrogen in a second step with a dehydrogenating catalyst which is purposely promoted by an acid whereby naphthenic components having pentamethylene rings are efficiently converted along with other reforming reactions. The dehydrogenation catalyst used in the second stage may contain as its essential ingredient one of the above-mentioned dehydrogenation promoters, e. g., platinum. The essential difference is that the dehydrogenation promoter is used in combination with an acidic material. Suitable acidic materials are silica-alumina composites, silica-magnesia composites, acid-treated clays, acid-treated alumina and other clay type cracking catalysts. The preferred materials are synthetic silica-alumina composites and alumina which has been partially converted to aluminum fluoride by treatment with hydrofluoric acid or another suitable fluorinating agent. The carrier material may be acidified during the catalyst preparation through the treatment with a hydrogen halide, e. g., hydrochloric acid, or the acid nature of the catalyst may be imparted during actual operation by treatment in use with a hydrogen halide or a substance producing hydrogen halide under reaction conditions. Such materials are, for example, benzene fluoride, ammonium fluoride, and tertiary butyl chloride.

The treating conditions, with the exception of the catalyst, can be substantially the same in the two stages of the treatment or they may vary within permissible limits as follows: Temperature, 450-500° C.; pressure, 30-100 atmospheres; WHSV 0.5-5; hydrogen/hydrocarbon mole ratio 3-10.¹

The conversion of 5-ring naphthenes into 6-ring naphthenes and the dehydrogenation thereof to aromatics are equilibrium reactions. By converting the 6-ring naphthenes present into aromatics in the first stage, it is achieved that in the second stage, when applying an acid dehydrogenation catalyst, the 5-ring naphthenes are converted into 6-ring naphthenes, which are dehydrogenated to aromatics under the reaction conditions. These successive treatments prevent considerable quantities of 6-ring naphthenes from being lost, either directly by hy-

¹ A variation of the process is described in U. S. Patent Number 2,550,531.

75 ¹ WHSV = weight hourly space velocity, which is the weight of the hydrocarbon feed passed over the weight of the catalyst in one hour.

drocracking or by the same reaction after conversion into 5-ring naphthenes. If the gasoline to be treated is passed immediately over the acid catalyst applied in the second stage, the isomerization of the 5-ring naphthenes into 6-ring naphthenes proceeds more slowly, so that the 5-ring naphthenes have more opportunity of developing side reactions while forming carbonaceous deposits.

In the process according to the invention there is only very slight fouling of the catalyst, so that the process can be carried out with very few interruptions.

The process of the invention is illustrated in the following example.

Example

A gasoline fraction with boiling point 113-191° C., O. N. F. —2=56, consisting of about 25% aromatic hydrocarbons, about 49% naphthenic hydrocarbons and 26% paraffins, and obtained by distilling crude petroleum, was hydroformed at a throughput rate of 2 kg. per litre of catalyst per hour together with 1000 litres of hydrogen per kg. of initial material, under a total pressure of 50 atm.:

1. According to a one-stage method over 50 millilitres of a commercial 100% nickel sulphide-tungsten sulphide catalyst with the following result:

Reaction temperature.....	° C.....	450	475	500
Yield C ₈ +	percent.....	98	97	95
Percent by weight of aromatics.....		41	50	53
O. N. F-2.....		65	69	72

2. According to a one-stage method over 50 millilitres of alumina-F-W-Ni=100:0.3:26.9:4.3-sulphidic catalyst, with the result:

Reaction temperature.....	° C.....	450	475	500
Yield C ₈ +	percent.....	96.5	91	83
Percent by weight of aromatics.....		35	39	46
O. N. F-2.....		69	72	76

3. According to a two-stage method, in the first stage 50 millilitres of catalyst as used according to (1) and in the second stage 50 millilitres of catalyst as applied according to (2) being used, with the following result:

Reaction temperature.....	° C.....	450	475	500
Yield C ₈ +	percent.....	95	89	82
Percent by weight of aromatics.....		44	55	66
O. N. F-2.....		70	78	82

The alumina-F-W-Ni-sulphide catalyst was prepared as follows:

Aluminum hydroxide was precipitated at a pH of from 8 to 9 by mixing an approximately 10% solution of AlCl₃-6H₂O with an approximately 2.5% NH₄OH solution. The precipitate obtained was filtered off and washed with 0.5% ammonia until all the halogen had been removed, after which it was re-washed with pure water.

A quantity of the precipitate, corresponding to 105 g. of dry substance, was treated with 15.6 g. of a 2.05% HF solution.

Subsequently 53.6 g. of (NH₄)₂ WS₄ was dissolved in 500 millilitres of water and 22 millilitres of 25% NH₄OH saturated with H₂S were added to the solution. To this mixture 44.5 millilitres of a solution of Ni(NO₃)₂, containing 101.3 g. of Ni per litre of solution, were added drop by drop. Subsequently acidification was carried out with about 58 millilitres of H₂SO₄ (25% by vol.) to a pH of 1.5.

The precipitate obtained was filtered off and mixed with the alumina treated with HF. The slurry was then

dried at 13 mm. of Hg while nitrogen was passed through at 140° C.

The catalyst was tabletted to tablets of 5 by 3 mm. after 1% of graphite had been added.

5 We claim as our invention:

1. Process for improving the anti-knock characteristics of naphthenic gasolines by catalytic treatment in the presence of hydrogen which comprises contacting the gasoline to be upgraded in the vapor phase in the presence

10 of hydrogen with a non-acidic dehydrogenation catalyst selective for the dehydrogenation of naphthenic hydrocarbons having hexamethylene rings at a temperature between 450° C. and 500° C. and a pressure between 30 and 100 atmospheres whereby naphthenic hydrocarbons having hexa-

15 methylene rings are dehydrogenated while the naphthenic hydrocarbons having pentamethylene rings remain substantially unaffected, then contacting the resulting partially converted gasoline in the vapor phase and in the presence of hydrogen with a solid acidic de-

20 hydrogenation catalyst at a temperature between 450° C. and 500° C. and a pressure between 30 and 100 atmospheres, whereby naphthenic hydrocarbons having penta-

methylene rings are substantially converted.

2. Process for improving the anti-knock characteristics of naphthenic gasolines by catalytic treatment in the presence of hydrogen which comprises contacting the gasoline to be upgraded in the vapor phase and in the presence of hydrogen with a catalyst consisting of a de-

25 hydrogenation promoter supported upon a carrier which is devoid of acidity at a temperature between 450° C. and 500° C. and at a pressure between 30 and 100 atmos-

30 pheres whereby naphthenic hydrocarbons having hexa-

35 methylene rings are selectively dehydrogenated while the naphthenic hydrocarbons having pentamethylene rings remain substantially unaffected, then contacting the resulting partially converted gasoline in the vapor phase and in the presence of hydrogen with a catalyst consisting of a de-

40 hydrogenation promoter supported upon an acidic cracking catalyst at a temperature between 450° C. and 500° C. and at a pressure between 30 and 100 atmos-

45 pheres whereby naphthenic hydrocarbons having penta-

50 methylene rings are substantially converted.

3. Process for improving the anti-knock characteristics of naphthenic gasolines by catalytic treatment in the presence of hydrogen which comprises contacting the gasoline to be upgraded in the vapor phase and in the presence of hydrogen with a catalyst consisting of plati-

45 num supported upon substantially pure silica at a tem-

50 perature between 450° C. and 500° C. and at a pressure

55 between 30 and 100 atmospheres whereby naphthenic hydrocarbons having hexamethylene rings are selectively dehydrogenated while the naphthenic hydrocarbons having pentamethylene rings remain substantially unaffected, then contacting the resulting partially converted gasoline

55 in the vapor phase and in the presence of hydrogen with a catalyst consisting of a dehydrogenating metal promoter supported upon an alumina which has been treated with hydrofluoric acid at a temperature between 450° C. and 500° C. and at a pressure between 30 and 100 atmos-

60 pheres, whereby naphthenic hydrocarbons having penta-

65 methylene rings are substantially converted.

4. Process for improving the anti-knock characteristics of naphthenic gasolines by catalytic treatment in the presence of hydrogen which comprises contacting the gaso-

65 line to be upgraded in the vapor phase in the presence of hydrogen with a catalyst consisting of sulfides of tungsten

70 and nickel supported upon a non-acidic carrier contain-

75 ing an alkali at a temperature between 450° C. and 500° C. and at a pressure between 30 and 100 atmospheres whereby naphthenic hydrocarbons having hexamethylene

rings are selectively dehydrogenated while the naphthenic hydrocarbons having pentamethylene rings remain sub-

stantially unaffected, then contacting the resulting par-

75 tially converted gasoline in the vapor phase and in the presence of hydrogen with a catalyst consisting of a de-

hydrogenation metal promoter supported upon an acidic hydrofluoric acid treated carrier.
